COMBINED CHAIR AND COLLAPSIBLE TRAY

Thomas Winrow, Naperville, Ill., assignor to Mohasco Industries, Inc., Amsterdam, N.Y., a corporation of New York

Filed Jan. 19, 1970, Ser. No. 20,980

Term of patent 14 years

Int. Cl. D6—01

U.S. Cl. D15—1

FIG. 1.

FIG. 2.

FIG. 1 is a perspective view of a chair embodying my new design.

FIG. 2 is a fragmentary perspective view showing the collapsible tray in extended position. The side not shown is like the side shown except for the omission of the tray, while the back of the chair is conventionally plain and unornamented.

I claim:

The ornamental design for a combined chair and collapsible tray, substantially as shown and described.
